UNITED STATES PATENT OFFICE.

RICHARD DACE WHITE, OF WASHINGTON, DISTRICT OF COLUMBIA.

DESIGN FOR LAMP SHADE.

Application filed September 12, 1924. Serial No. 10,763. Term of patent 3½ years.

To all whom it may concern:

Be it known that I, RICHARD DACE WHITE, a citizen of the United States of America, and a resident of Washington, in the District of Columbia, have invented a new, original, and ornamental Design for Lamp Shade, of which the following is a specification, reference being had to the accompanying drawing, forming a part hereof.

I claim:

The ornamental design for lamp shade as shown and described.

RICHARD DACE WHITE.
